Primary Examiner — Mimosa De(74) *Attorney, Agent, or Firm* — Hanley, Flight & Zimmerman, LLC(57) **CLAIM**

The ornamental design for a seating device, substantially as shown and described.

DESCRIPTION

FIG. 1 is a front perspective view of an ornamental design for a seating device;

FIG. 2 is a front view thereof;

FIG. 3 is a rear view thereof;

FIG. 4 is a left elevation view thereof;

FIG. 5 is a right elevation view thereof;

FIG. 6 is a top view thereof; and,

FIG. 7 is a bottom view thereof.

The dashed lines shown on the fabric of the backrest and seat represent stitching.
